SUITCASE

Marvin H. Sherman, Encino, Calif., assignor to Standard Luggage of Los Angeles, Los Angeles, Calif., a co-partnership

Filed Dec. 2, 1960, Ser. No. 63,087

Term of patent 7 years

(Cl. D87—5)

Fig. 1 is a side elevational view of a suitcase showing my new design;

Fig. 2 is an end elevational view thereof;

Fig. 3 is a top plan view thereof; and

Fig. 4 is a bottom plan view thereof.

The dominant features of the design reside in the portions shown in full lines.

I claim:

The ornamental design for a suitcase, as shown and described.
